JOHN SHEFFMAN, OF NEW YORK, N. Y.

MACHINE FOR TREATING CHOCOLATE MASSES.

1,103,627.

Specification of Letters Patent. Patented July 14, 1914.

Application filed January 13, 1914. Serial No. 811,872.

To all whom it may concern:

Be it known that I, JOHN SHEFFMAN, a subject of the Emperor of Austria-Hungary, and resident of the city of New York, in the 5 county of New York and State of New York, have invented certain new and useful Improvements in Machines for Treating Chocolate Masses, of which the following is a specification.

10 The present invention relates to a machine for treating chocolate masses, and more particularly to an apparatus in which the chocolate mass is subjected to mechanical treatment to obtain a ready melting of 15 the same.

In the manufacture of chocolate cocoa is mixed with sugar in a suitable mixing machine, and the mass so obtained is then in the so-called "conches" subjected to further treatment in order to refine, as it were, the mass, and to incorporate it in a suitable fat, for instance cocoa butter, in order to obtain a ready melting of the mass, which is desirable in the further steps of the process 25 of manufacture of chocolate. It has been found that these conches do not fully perform the required work and that, on the other hand, their parts are subjected to wear owing to their reciprocating motion.

30 One of the objects of the present invention is to provide a machine that takes the place of the conches above mentioned, but which is in all respects more effective in operation than the conches, and does away with all the 35 defects of the latter.

Another object of the invention is to produce a machine of the character described which can be manufactured on a commercial scale, or in other words one which is not 40 so difficult to produce as to be beyond the reasonable cost of such an apparatus.

With these and other objects in view, which will more fully appear as the nature of the invention is better understood, the 45 same consists in the combination, arrangement and construction of parts hereinafter fully described, pointed out in the appended claims and illustrated in the accompanying drawings, it being understood that many 50 changes can be made in the size and proportion of the several parts within the scope of the appended claims without departing from the spirit or sacrificing any of the advantages of the invention.

55 One of the many possible embodiments of

the invention is illustrated in the accompanying drawings, in which:—

Figure 1 is a front elevation of a machine constructed in accordance with the present invention; Fig. 2 is a vertical longitudinal 60 cross section taken through the same, partly in elevation; and Fig. 3 is a plan view of a detail of construction; and Fig. 4 is an end elevation of a roller employed therein.

In the drawings, the numeral 10 indicates 65 the base frame of the apparatus. This frame, preferably a casting, is casing-shaped, its lower end being provided with a flange 11, that rests upon the floor, to which it is attached by means of screws 12, or otherwise. The base frame supports a vessel 13 which is cup-shaped, its bottom 14 being flat, and its side wall 15 slanting, as shown in Fig. 2 of the drawings. Near the upper edge of the side wall is formed a flange 16, 70 that rests upon the frame 10, the vessel itself being disposed within the frame in such a manner that an annular space 17 is formed between the walls of these two elements, thereby forming a jacket around the vessel 75 13. From the bottom 14 of the vessel 13 rises centrally a step bearing 18. The vessel 13 is covered by a hood 19, that is provided with an air inlet 20, in which are disposed baffle plates 21. An air outlet 22 is arranged 80 in the top of the hood for a purpose hereinafter to be described. In the hood is furthermore provided an opening 23, which is adapted to be closed by doors 24, 24. The mass to be treated is placed in the vessel 85 90 through this opening.

To the sides of the base frame 10 and to the floor are attached vertical standards 25 and 26, which extend above the hood 19, and are connected by a transverse member 27. 95 To the standard 26 is fastened a bracket 28, provided with a bearing 29, which is arranged in alinement with the bearing 30, that is either made integral with or fastened to the standard 26. In the bearings 29 and 100 30 is journaled a shaft 31, carrying a loose pulley 32 and a fixed pulley 33, and furthermore a bevel gear 34, which meshes with a similar gear 35, that is mounted upon a vertical shaft 36, which is journaled in the 105 step bearing 18 and in a bolster bearing 37, that is, preferably, made integral with the transverse member 27. With the step bearing may be associated a ball bearing 38 for 110 the well known purpose. To the vertical

shaft 36 is keyed or otherwise attached a substantially Y-shaped horizontally arranged supporting member 39, to the leg 40 of which is pivotally fastened a bail-shaped 5 downwardly extending bracket 41, carrying a spindle 42, that is held against rotation on said bracket. On this spindle is rotatably disposed a conical roller 43, which is made of granite. A scraper 44 is pivoted to the 10 bracket 41, said scraper extending throughout the length of the roller 43 and being kept in contact with the same by means of lugs 45, which are screwed or otherwise attached to the bracket 41. To the legs 46 of 15 the Y-shaped member 39 are fixedly attached downwardly extending members 47, which carry stirring arms 48 and scrapers 49, the latter bearing against the slanting side walls 15 of the vessel 13. The granite roller 43 20 cooperates with a bed stone 50, preferably made of granite, and held upon the flat bottom 14 of the vessel 13 by cementing material 51. This bed stone is ring-shaped and is brought in proper relation to the roller 25 by set screws 52. After having been brought in proper relation, the cementing material is caused to flow between the bottom 14 and the bed stone and left to set.

An outlet pipe 53 communicates with the 30 vessel 13, a cock 54 being inserted in said pipe. Below the bottom 14 of the vessel 13 is disposed a heating means, for instance in the form of a steam coil 55, valves 56 and 57 controlling the flow of the steam therein.

35 The operation of this device is as follows: The chocolate mass with the proper amount of fat, for instance cocoa butter, is placed into the vessel 13 and steam admitted into the coil 55. Rotation is then imparted to 40 the countershaft 31 and thus to the parts carried by the shaft 36. The mass in the vessel 13 is ground very fine by the coöperating granite roller 43 and the bed stone 50, and thoroughly mixed with the fat. In the 45 chocolate such amount of fat must be incorporated so as to cause the entire mixture to melt by the heat applied thereto. The stirring arms 48 obviously serve to thoroughly agitate the mass, the scrapers 49 50 causing the mass adhering to the side wall of the vessel to fall toward the center thereof, that is into the path of the roller 43. Inasmuch as this roller is conical, it tends to cause the mass in the receptacle to move 55 toward the center while being acted upon, in contradistinction to similar grinding or rubbing devices which usually throw the mass toward the walls of the containers. In causing the mass to flow toward the center of the 60 vessel, obviously it is continuously acted upon by the said roller. The scraper 44, of course, removes the material that adheres to the roller 43 from the latter. It is obvious that the angular velocity of the roller 43, 65 which is bodily rotated around the longi-

tudinal axis of the apparatus, gradually increases from its inner end toward its outer end. Inasmuch as this roller rotates, however, around its own axis, it is obvious that by reason of its conical shape, the angular 70 velocity of the peripheral portion of its inner edge relative to its own axis is considerably smaller than that of the peripheral portion of its outer edge. The angular velocities of a portion of the roller relative to its 75 own axis and relative to the vertical axis of the apparatus are thus, by making the roller cone-shaped, made to correspond substantially to each other, whereby undue friction between the roller and the bed stone is effectively prevented, thus necessitating little power only to drive the machine. When the treatment of the mass has been finished, the cock 54 is opened, the molten mass flowing then through the pipe 53 into a container. 80 The scrapers 49 will facilitate the drawing off of the mass, the machine being operated until the mass has nearly been removed.

The gases or foul odors, which are produced in treating the chocolate mass, are 85 carried away through the outlet 22 in the top of the hood by the fresh air entering through the inlet 20. The jacket around the vessel 13 serves to prevent the escape of heat from said vessel.

90 It has been found that the machine herein described performs the work of the conches above mentioned in about one-half of the time that is needed for the treatment in the 95 said conches.

100 What I claim is:—

1. In a machine of the character described, the combination with a cup-shaped vessel provided upon its bottom with a bed stone, of a vertical rotary shaft centrally disposed in said vessel, a supporting member keyed to said shaft, a bracket pivotally attached to said supporting member, a conical roller carried by said bracket and coöperating with said bed stone, the axis of said conical roller being disposed at an angle to the axis of said shaft and the base of the roller forming the outer end thereof, a downwardly extending member fixedly attached to said supporting member, stirring arms upon said downwardly extending member, and a scraper also upon said downwardly extending member, said scraper bearing against the side wall of said vessel.

110 2. In a machine of the character described, the combination with a cup-shaped vessel provided upon its bottom with a bed stone, of a vertical rotary shaft centrally disposed in said vessel, a supporting member keyed to said shaft, a bracket pivotally attached to said supporting member, a conical roller carried by said bracket and coöperating with said bed stone, the axis of said conical roller being disposed at an angle to the axis of said shaft and the base of the roller forming 115 120 125 130

the outer end thereof, a hood covering said vessel, means for heating said vessel, a downwardly extending member fixedly attached to said supporting member, stirring arms upon said downwardly extending member, and a scraper also upon said downwardly extending member, said scraper bearing against the side wall of said vessel.

3. In a machine of the character described, 10 the combination with a cup-shaped vessel provided upon its bottom with a bed stone, of a vertical rotary shaft centrally disposed in said vessel, a supporting member keyed to said shaft, a bracket pivotally attached to 15 said supporting member, a conical roller carried by said bracket and coöoperating with said bed stone, the axis of said conical roller being disposed at an angle to the axis of

said shaft and the base of the roller forming the outer end thereof, a hood covering said vessel, heating means arranged below the bottom of said vessel, a downwardly extending member fixedly attached to said supporting member, stirring arms upon said downwardly extending member, and a 25 scraper also upon said downwardly extending member, said scraper bearing against the side wall of said vessel.

Signed at New York, in the county of New York, and State of New York, this 30 6th day of January, A. D. 1914.

JOHN SHEFFMAN.
